UNITED STATES PATENT OFFICE.

FRANK LOWRY, OF STEUBENVILLE, OHIO, ASSIGNOR TO THE OHIO GREASE COMPANY,
OF LOUDONVILLE, OHIO, A CORPORATION OF OHIO.

GREASE LUBRICATOR.

1,131,639.

Specification of Letters Patent.

Patented Mar. 9, 1915.

Application filed June 13, 1912. Serial No. 703,369.

To all whom it may concern:

Be it known that I, FRANK LOWRY, a citizen of the United States, residing at Steubenville, in the county of Jefferson and State 5 of Ohio, have invented certain new and useful Improvements in Grease Lubricators, of which the following is a specification.

The invention relates to improvements in grease lubricators of the general class set forth in Letters Patent No. 803,296, reissued as No. 13,269; No. 803,297, reissued as No. 13,270; No. 946,450; and No. 946,484; and the object of the present invention is to provide a lubricator which will more completely heat the grease, under all external conditions of temperature, and maintain the same in the heated condition necessary or desirable for atomizing the grease for most efficiently lubricating all the parts of the engine. 15 The efficiency of lubricators of this class depends largely upon the temperature to which the grease is heated and maintained, for the reason that, when the grease is more highly heated, it is reduced to a thinner liquid 20 which permits the formation of drops of a minimum size, thus giving a maximum control of the quantity of lubricant fed into the steam supply line; and, at the same time, the more highly heated and smaller sized 25 drops permit the lubricant to be more thoroughly atomized so that it will more completely vaporize and saturate the live steam in the supply line.

The object of the improvements, thus referred to, is attained by locating the feed chamber wholly within the grease chamber, and by providing a vertical straight-way port in one end of the feed chamber leading directly from the grease chamber, and a lateral delivery tube leading from the other end of the feed chamber to the steam line, with a steam pipe entering the opposite side of the chamber co-axial with the delivery tube, whereby the liquid grease will flow 40 directly from the grease into the feed chamber without any change of direction, and will be positively atomized and driven into the delivery pipe by live steam from the steam pipe, without being chilled at any 45 point in the feed line thus formed.

The invention, thus set forth in general terms, is illustrated with respect to two slightly modified forms thereof in the accompanying drawings, in which—

55 Figure 1 is a vertical section of a pre-

ferred form of the improved lubricator; Fig. 2, a cross section thereof on line 2—2, Fig. 1; Fig. 3, a cross section thereof on line 3—3, Fig. 1; Fig. 4, a vertical section of a slight modification of the preferred form of 60 the improved lubricator; Fig. 5, a cross section of the same on line 5—5, Fig. 4; and Fig. 6, a cross section on line 6—6, Fig. 4.

The same or similar numerals refer to the same or similar parts throughout the drawings.

The grease reservoir or chamber 1 or 1^a is formed by the outer case 2 or 2^a of the lubricator, and the feed chamber 3 or 3^a is formed by the inner case 4 or 4^a; the walls 70 of which inner case are preferably located wholly within the walls of the outer case, with a free intervening space or interval on all sides and at both ends, as shown in Figs. 1, 2 and 3, but may have one side wall there- 75 of formed integral with the external case, as shown in Figs. 4, 5 and 6.

For a drop feed lubricator, the feed port 5 is formed in the nipple 6 centrally formed or secured in the upper wall of one side wall 80 of the inner case 4 forming the feed chamber, and this port is vertically positioned so that the grease can flow directly downward without any change of direction from the contents of the grease chamber above the 85 feed chamber. The feed valve 7 is mounted by its stem 8 in the upper end of the outer case, which valve is adapted to seat in the upper end of the feed port, and, by proper adjustment, to control the flow of liquid 90 grease therethrough.

The transverse delivery tube 9 or 9^a extends through the separate walls of the outer and inner cases and the intervening interval, in the form of lubricator shown in Fig. 1, or 95 extends through the common wall of said cases, as shown in the modified form in Fig. 4; and this tube leads laterally from the lower end of the feed chamber, and its outer end communicates with the delivery pipe 100 10, which leads into the steam supply line 11, and is preferably provided with the stop valve 12, as shown in the drawings. The transverse steam tube 13 or 13^a extends through the separate walls of the outer and 105 inner cases, and the intervening interval at the lower end of the feed chamber, on the opposite side from and co-axial with the delivery tube, so as to discharge across the bottom of the feed chamber into the delivery 110

tube, and the outer end of the steam tube communicates with the steam pipe 14 which leads from the three-way fitting 15 in which is preferably provided the steam-regulating valve 16. The three-way fitting 15 communicates with a source of live steam by a pipe, not shown, as, for instance, with the steam line 11 above the delivery pipe connection therewith; and the three-way fitting 10 also communicates with the condensing pipe 17 which may be provided with the condensing chamber 18, and leads to the condensing tube 19 which opens into the lower portion of the grease chamber; which condensing tube 15 is preferably provided with the stop valve 20.

Sight glasses 21 are provided in opposite sides of the upper end of the outer case in the plane of the entrance to the feed port, so that the level of the oil in the lubricator with reference to the opening of the feed port may be viewed from either side of the lubricator; and the sight glasses 22 are provided in opposite sides of the upper end of 25 the inner case in the plane of the lower end of the feed jet, the tubular connection 23 being provided around the sight glasses 22 through the adjacent walls of the outer and inner cases and the intervening intervals, so 30 that the formation of drops of grease on the lower end of the feed jet may be viewed from either side of the lubricator.

The usual feed plug 24 is provided in the upper end of the outer case 2 or 2^a through 35 which the grease chamber 1^a or 1^a is filled with grease or other lubricant; and the usual drain plug 25 and drain valve 26 being provided in the lower end of the outer case for draining off the water of condensation.

In use, the grease chamber is filled with grease or other lubricant, and the steam valve 15, the condensation valve 19, and the delivery-pipe valve 11 are opened. The 45 water of condensation formed in the condensing pipe and chamber flows downward through the condensing tube into the lower end of the grease chamber, and live steam flows through the steam pipe and the steam tube into and across the lower end of the feed chamber into the delivery tube, and 50 also rises upward into and fills the feed chamber. The heat radiating from the condensing tube 19, the steam tube 13 or 13^a and more particularly from the inner case 4 or 4^a around the feed chamber, heats the lubricant in the grease chamber to a liquid form, and the same floats upon the water of condensation as it rises in the grease chamber. The feed valve 7 is then opened, according to the rate of feed desired, and the 55 liquid grease flows directly downward from the grease chamber through the straightway feed port, and forms a drop on the lower end of the nipple 5. The drop, when

fully formed, then falls downward to the lower end of the feed chamber, where it is impinged by the live steam flowing across the same from the steam tube, and is atomized and driven through the delivery tube 70 into the feed pipe and steam line in the manner set forth in the prior Patent No. 946,450, above referred to.

It is evident that the location of the feed chamber entirely within the grease chamber 75 not only conserves the heat within the feed chamber, but such heat as radiates therefrom serves to heat the surrounding lubricant; that there is a direct communication from the body of grease in the grease chamber, without any change of direction through the straight-way feed port, into the feed chamber; that there is no change of direction of the grease from the time it enters the upper end of the feed port until it is 80 driven into the delivery tube, excepting only when it is impinged by the flow of steam from the steam tube; and finally that the grease is at all times kept at the maximum degree of temperature from the time 85 it leaves the grease chamber until it is vaporized and driven into and through the delivery tube.

I claim:

1. A lubricator including an outer case 95 forming a grease chamber, an inner case forming a feed chamber within the grease chamber with a spaced interval between the upper walls of the cases, a straightway feed port in the upper wall of the inner case 100 communicating directly downward from the grease chamber into the feed chamber, a delivery tube leading laterally from the lower end of the feed chamber, and a steam tube leading through the grease chamber 105 into the feed chamber and discharging across the bottom thereof into the delivery tube.

2. A lubricator including an outer case forming a grease chamber, an inner case 110 forming a feed chamber within the grease chamber with spaced intervals between the upper and lower walls of the cases, a straightway feed port in one end wall of the feed chamber leading directly from the 115 grease chamber into the feed chamber, a delivery tube leading laterally from the other end of the feed chamber, and a steam tube leading through the grease chamber into the feed chamber and discharging 120 across the same into the delivery tube.

3. A lubricator including an outer case forming a grease chamber, an inner case having certain of its walls including the top wall spaced bodily within the walls of 125 the outer case forming a feed chamber therein, a feed port in said top wall of the inner case communicating from the grease chamber into the feed chamber, a delivery tube leading laterally from the other end 130

of the feed chamber, and a steam tube leading through the grease chamber into the feed chamber and discharging across the same into the delivery tube.

5 4. A lubricator including an outer case forming a grease chamber, an inner case having its walls spaced bodily within the walls of the outer case forming a feed chamber therein, a feed port in the upper end 10 wall of the inner case communicating from

the grease chamber into the feed chamber, a delivery tube leading laterally from the lower end of the feed chamber, and a steam tube leading through the grease chamber into the feed chamber and discharging into 15 the delivery tube.

FRANK LOWRY.
